US0D1113661S

(12) **United States Design Patent** (10) **Patent No.:** **US D1,113,661 S**
(45) **Date of Patent:** **** Feb. 17, 2026**

(54) **CHARGER**

(71) Applicant: **Jinfeng Huang**, Shenzhen (CN)

(72) Inventor: **Jinfeng Huang**, Shenzhen (CN)

(**) Term: **15 Years**

(21) Appl. No.: **29/997,613**

(22) Filed: **Apr. 8, 2025**

(51) LOC (15) Cl. **13-02**

(52) U.S. Cl.

USPC **D13/108**

(58) **Field of Classification Search**

USPC D13/103, 107, 108, 110, 118, 119, 137.1,
D13/137.2, 137.3, 137.4, 138.1, 138.2,
D13/139.1

(57) **CLAIM**

The ornamental design for a charger as shown and described.

DESCRIPTION

FIG. 1 is a front, right, top perspective view of a charger showing my new design;

FIG. 2 is a rear, left, bottom perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof; and,

FIG. 8 is a bottom plan view thereof.

The broken lines in the drawings depict portions of the charger and form no part of the claimed design.

1 Claim, 8 Drawing Sheets
